UNITED STATES PATENT OFFICE

127,030

DESIGN FOR A COMBINED MAGNIFYING AND ILLUMINATING DEVICE

Carl W. Bettcher, New Haven, Conn., assignor to
The Eastern Machine Screw Corporation, New
Haven, Conn., a corporation of Connecticut

Application March 10, 1941, Serial No. 99,486

Term of patent 7 years

To all whom it may concern:

Be it known that I, Carl W. Bettcher, a citizen
of the United States, residing at New Haven, in
the county of New Haven and State of Connec-
ticut, have invented a new, original, and orna-
mental Design for a Combined Magnifying and
Illuminating Device, of which the following is a
specification, reference being had to the accom-
panying drawing, forming part thereof, wherein,

Figure 1 is a perspective view of the combined

magnifying and illuminating device showing my
new design.

Figure 2 is a side elevational view of the device.

The essential features of the design reside in
the parts shown in full lines in the drawing.

I claim:

The ornamental design for a combined mag-
nifying and illuminating device, as shown and de-
scribed.

CARL W. BETTCHER.
